STRETCHING MACHINE

Fritz Singer, Starnberg, and Alfred Liebergeld,
Nuremberg, Germany; said Liebergeld assignor
to said Singer

Application June 29, 1938, Serial No. 216,484
In Germany June 30, 1937

6 Claims. (CL. 84—19)

This invention relates to an apparatus for producing solid metal articles like plates, sheets, strips and the like, the longitudinal cross section of which is uniformly or non-uniformly varying in thickness.

The invention herein disclosed bears a close association with the invention disclosed in Patent No. 1,982,544, entitled "Method and apparatus for elongating metal articles," granted November 27, 1934, to Fritz Singer, one of the joint inventors herein, to which patent reference is hereby invited. In that document there is disclosed a machine for uniformly reducing the thickness of sheets, strips, plates and the like, and the present invention is built along the lines of the invention disclosed in the patent referred to, embodies the principles thereof, but additionally includes means for varying uniformly or otherwise the thickness that is imparted to the work during the reducing operation. Thus, it is possible to make a strip or plate of uniform taper or one of some special shape, the thickness of which varies but not in a uniform manner.

In accordance with the foregoing, a feature of our invention resides in the provision of means adapted to reduce or increase the space between the reducing roll and the article carrier in the intervals between successive reducing or stretching strokes. In case the gap between the roll and the article carrier is intended to be increased, such increasing can be done after the completion of a stretching stroke and during the return stroke of the machine. However, in the event that such space should be decreased, such decreasing can only be effected toward the end of the return stroke and in the beginning of the stretching stroke.

The variations of the distance between the roll and the article carrier might also be accomplished by lifting and lowering the article carrier rather than the roll, inasmuch as it is only a question of construction suitability whether the article carrier is reciprocated in order to effect the stretching operation or the roll is reciprocated for the same purpose. Also the controlling devices for lifting and lowering the article carrier or the roll, as herein disclosed, may be of various designs and it is only a question of the most simple and effective construction as to which of the numerous possibilities of modern gearing and constructive techniques is made use of. Inasmuch as the apparatus of the type illustrated in Figures 6, 7 and 8 of Patent No. 1,982,544, hereinabove referred to, permits unprecedented reduction rates to be obtained, the apparatus constructed in accordance

with the present invention is intended to produce in a single operation articles having ends of different thickness. In accordance with the invention disclosed in the above mentioned patent the material is not rolled in the manner of the known rolling processes but is worked by spreading out portions of the article projecting beyond the rolling surface of the article carrier in the direction in which elongation takes place and reduction is effected with a consumption of energy considerably less than is required for known rolling processes, and furthermore, inasmuch as the roll is not subjected to strains of flexure vertically to the article, but only parallel thereto, the smallest clearances of thickness may be obtained without necessitating the use of arched rolls.

Other objects and features of our invention will become apparent from a reading of the following specification in the light of the accompanying drawings, in which:

Figures 1 to 4, inclusive are side elevations of the stretching apparatus, mainly in section, showing the parts of the apparatus in different subsequent phases of the stroke, as follows: Figure 1 illustrates the position of the machine parts after finishing a return stroke; Figure 2 the position of the parts before the beginning of the stretching operation proper; Figure 3 after finishing the stretching operation; and Figure 4 before feeding the article forward for the following stretching operation;

Figure 5 is a view of the machine taken in section through Figure 6; and

Figure 6 is a front elevation of the apparatus with the crank drive in the foreground.

There is disclosed in the patent already referred to a machine designed for reducing the thickness of elongated metal articles such as strips, plates, sheets and the like, by advancing the article, increment by increment, to a rotary roll and permitting the roll to reduce the thickness of the article, increment by increment, in accordance with the gap or space between the roll and the smooth surface over which the work is being fed. This latter surface, although smooth, is interrupted in a most important manner, as described in the patent, in order to effect the reduction. The present invention incorporates the features and designs of construction and operation shown in the patent, and accordingly reference is invited to the patent for an understanding of the basic invention. The main purpose of the present contribution is to so modify the machine disclosed in the patent that instead of producing

articles of uniform cross section it will be capable of producing articles of varying cross section.

Construction of machine

5 On a base plate 10 there are mounted four vertical columns, 12, 12' and 14, 14', the upper ends of which are connected together by means of a cross head 16. Within recesses of the columns 12, 12' and 14, 14' are positioned bearings 18, 18' and 20, 20' which are adapted to receive and support the journals 22, 24 of a reducing roll 25.

As shown in Figure 5, the bearings 18 and 20 are formed on the upper extremities of shafts 26, 28, which shafts are mounted in vertical bores 30, 32 for vertical movement against the action of compression springs 34, 36.

20 A plurality of wedge blocks 38, 40 are associated with the cross head 4, and are adapted to cooperate with a double wedge member 42, 44 mounted immediately above the bearings 18' and 20'. The compression springs 34 and 36 may be replaced by any suitable supporting devices such as hydraulic cylinders and serve to maintain the bearings 18, 20, the roll 25, the bearings 18', 20', and the double wedge block 42, 44 in upper, assembled position.

25 The double wedge 42, 44 carries a screw member 48 which is engaged by an interiorly screw threaded nut 50. The latter is rotatably supported on a bearing 52 carried by a bracket arm 54 extending outwardly from the machine frame and is provided at its outer extremity with a hand wheel 56, by means of which the nut may be rotated to impart reciprocation to the screw 48 and the attendant double wedge member 42, 44. It will be understood that the roll 25 may thus be raised and lowered by rotation of the hand wheel 56 and the nut 50.

30 In order to produce solid metal articles the thickness of which varies either uniformly or non-uniformly, means must be provided for controlling the movement of the double wedge in order to vary and to regulate the sequence and amount of movement of the roll 25, toward or away from the work piece or metal stock. In certain instances the hand wheel 56 may suffice for this purpose but in many instances the rapid sequence of strokes in the operation of the machine will not permit sufficient time for manual operation. 35 This observation is particularly significant with respect to uniformly tapered sheets or plates.

35 Accordingly, a pawl and ratchet arrangement is provided for automatically or mechanically operating the roll control mechanism, which latter includes the screw 48, the nut 50, and the double wedge member 42, 44. As illustrated, a detent or pin 60 is mounted eccentrically on the journal shaft 22 and is arranged to engage a projection 62, extending laterally from a lever 63, on each rotation of the reducing roll 25. The double arm, or bell crank, lever 63 carries a pawl 64 at its lower end, which pawl is urged, by means of a spring 66, into engagement with a ratchet wheel 68, and at its upper extremity is provided 45 with an extension 70 which, by means of a spring 72, is urged into engagement with an adjustable abutment 74.

40 The ratchet 68 may be formed integrally with the nut 50 in order that all movement imparted to the ratchet will be conveyed to the screw 48 and wedge bar 42, 44. Thus, in operation, each time the reducing roll 25 rotates, the pin 60 strikes the projecting arm or pin 62, causing the pawl 64 to engage the teeth of the ratchet 68, there- 45 by imparting partial rotation to the nut 50 and

some slight amount of endwise movement to the screw 48.

45 The base plate 10 of the machine is provided with a plurality of bearings 80, 82 which receive a crank shaft 84 for driving the machine. The shaft 84 is connected with a suitable source of power and drives a connecting rod or drive shaft 86 which, by means of a connecting pin 88, has driving engagement with a carriage 90. The carriage 90 is mounted to reciprocate on a wedge shaped slide-block 92 and is guided in this movement by means of a guide bar 94, the upper lengthwise portion of which slides in a groove formed in the carriage 90 and the lower lengthwise portion of which slides in a groove formed 15 in the slide-block 92. This latter member 92, is, in turn, guided within a recess 96 formed within the base, as shown in Figure 5. The carriage 90 supports an elongating surface 91 lying in a horizontal plane and a supporting surface 93, the two surfaces being inclined toward one another and intersecting at some point as 95.

20 In order to hold the article being worked out of contact with the roll during the return stroke of the latter, the slide-block 92 must be periodically lowered and periodically raised to bring the work into engagement with the roll on the forward or reducing stroke of the latter and to move it out of engagement during the return. To this end, the movement of the carriage 90 during certain portions of the stroke is transmitted to the slide-block 92 by means of abutments 100, 102 formed on the carriage, engaging or striking the opposite extremities of a reciprocal guide bar 104. The reciprocal bar 104 is guided within a recess 35 formed in the slide-block 92 and is arranged to co-operate with a plurality of abutments 106, 108 in a manner hereinafter to be more completely described. These members 106, 108 are mounted within recesses formed in the base plate 40 10 and are adapted to be depressed within the recesses by means of the bar 104 against the action of the compression springs 110 and 112. The abutments or members 106, 108 are provided with shoulders 114, 116 and 118, 120 for a purpose presently to be described.

25 In order to hold the article rigid on the carriage during the stretching or working stroke of the roll, a friction plate 122 is provided and this plate is arranged to press against the article and the carriage by means of compression springs 124, 126 arranged on bolts or bars 128. In order to permit the article to be advanced into a new stretching position after each operation of the stretching or reducing roll, the friction plate must be arranged to release the work piece periodically and to this end there is provided a bracket member 130 mounted on the carriage and a bell crank lever 132 mounted on the bracket. The short extremity of the bell 60 crank 132 is connected with the brake, or presser plate 122, by means of a link, as shown, and the long arm carries a cam roller 134 engaging a path 136 formed on a cam plate 138.

30 Feeding of the article during the stretching operation is brought about by apparatus now to be described. A sliding feed block 140 is guided within a recess 142 formed within the carriage and is actuated or reciprocated by means of a bell crank lever 144 which is pivoted at 146 to an extension 148 of the carriage. The upper extremity of the bell crank engages within a recess formed in the sliding feed block 140 and the lower end is adapted to be engaged alternately by a stationary abutment 150 and a spring pressed 75

abutment 152 adjustably secured to the base plate. The extent of reciprocal movement of the sliding feed block 140 is controlled by an adjustable abutment 154 carried by the carriage 5 extension and, in the opposite direction, by a second abutment 156 carried by the block itself.

Mounted in cooperative relationship to the sliding feed block 140 is a friction plate or feeding device 158, movement of which is controlled 10 by means of a toggle mechanism comprising a bracket arm 160, a bell crank lever 162, and a link 164. The lever 162 carries a cam roller 166 which moves over a cam path 168 formed on the cam plate 138 and during operation of the machine, as about to be described, this toggle mechanism serves to actuate the clamping or feeding mechanism.

There remains only one feature of construction of the machine that has not been described, 20 namely, the apparatus for driving the reducing or stretching roll. As illustrated, the roll is provided with a pinion gear 170 rigidly fixed to the journal 22, as shown in Figure 5. A rack 172 is carried by the carriage 90 for reciprocal movement therewith and engages a toothed wheel 174 carried by a shaft 175 mounted in a bearing 176 formed in the column 14. On the end of the shaft opposite the gear 174 is a second gear 178 which engages an idler gear 180 loosely mounted 30 on a shaft 182 carried by a swinging arm 184. The arm is adapted to swing about the shaft 175 and its position with respect thereto may be fixed by means of a bolt 186, the shank of which passes through an arcuate opening 188 formed in 35 the arm 184.

This arrangement of the mechanism for driving the reducing roll permits the driven gear 178 of Figure 6 to be substituted by gears of different sizes to vary the peripheral speed of the 40 reducing roll within certain limits. In case the stretching operation is to be performed without driving the roll 25, the swinging arm is secured in such a manner that the gears 170 and 180 are out of engagement with one another.

15

Operation of machine

In operation, the position of the reducing roll is adjusted by means of the hand wheel 56 in order to obtain the desired initial wall or work thickness. In the position of the stretching machine parts, as illustrated in Figure 3, the work to be stretched, which generally is a strip, a sheet or the like, is placed on the carriage 90 and passed through the clamping mechanism 140, 158 until it is engaged by the friction plate or jaw 122, whereupon the machine is placed in motion. After several idle rotations of the crank the end of the article will have been fed past the clamping device 122 into position to be engaged 0 by the reducing roll 25. In order to illustrate the production of an article having a uniformly tapered thickness, the illustrations show the operation of the machine in the midst of a stretching operation rather than at the beginning or commencement thereof. Figure 1 illustrates the position of the press or stretching machine parts after the carriage 90 has finished its return stroke. During the completion of the return stroke the abutment 102 has forced backward 5 the slide-block 92 and the guide bar 104, thus lifting the carriage 90 into its working position. The slide-block 92 is held in this position by means of the shoulders 118, 116 of the abutments 106 and 108. The work has then been advanced 10 into a new stretching position and is clamped

between the friction plate 158 and the cooperating member 140, which, in turn, is secured against movement in the direction of stretching by means of the abutment 156 engaging the carriage of the machine.

The clamping device 122 is still open. The crank shaft 84 is rotating in the direction of the arrow of Figure 1 and moves the carriage 90 to the right of the position therein illustrated, causing the rollers 134 and 166 to move out of 10 engagement with the cam sections 136 and 168 into the position illustrated in Figure 2, and additionally causing the compression springs 124, 126 to press the friction plate 122 into firm engagement with the article or work. Meanwhile 15 the clamping and feeding device 140, 158 still remains closed due to the self-locking action of the toggle levers 162 and 164. The roll 25 comes into contact with the article and the stretching operation begins. By means of the rack and 20 pinion gear arrangement, hereinbefore described, the roll 25 is rotated in anti-clockwise direction.

During the continued rotation of the crank 84 the abutment 100 pushes on the left end of the guide bar 104 which is then moved to the right 25 and forces downwardly the member 108 by the sloped portion of the guide bar having engagement therewith. At this point the cam roller 166 strikes on the abutment positioned at the extreme right of the cam plate 138, whereby the 30 toggle lever 162, 164 is broken, thereby lifting the clamping plate 158. As soon as the abutment 100 touches the slide-block 104 the stretching operation is completed. In the meantime the abutment 108 has been depressed by means of the 35 sloping shoulder formed on the guide bar 104 so that the slide-block 92 comes out of contact with the shoulder 116 formed on the member 108. In this position the free end of the lower arm of the bell crank lever 144 engages the spring actuated 40 abutment 152 and the projecting pin 60, carried by the journal 22, strikes the cooperating pin 62 of the pawl and ratchet gearing.

During the last part of the movement to the right of the carriage 90 the guide bar 104 is, by 45 means of the abutment 100, moved to the right in a downwardly sloping path and it contacts the shoulder 120 of the member 108. Thereby the carriage 90 is lowered so that the article being stretched moves out of contact with the reducing 50 roll 25. Simultaneously the slide-block 92 permits the member 108 to be lifted into its upward position by means of the compression spring 110. The shoulders 114, 120 thus hold the slide-block 104 in its lowermost position.

The lower arm of the bell crank lever 144 is held fast by engagement with the abutment 152 and as the pivot point of the lever participates in the further movement to the right of the carriage 90 the slide-block is, by means of the upper 60 arm of the lever, pushed to the right until it contacts the abutment screw 154. The actuating pin 60 which projects from the journal 22 imparts a clockwise rotation to the lever 63, which rotation is in turn transmitted to the ratchet wheel 68 by 65 means of the pawl 66. The ratchet wheel 68 being secured to the nut 50 and the nut 50 being rotatably mounted in the bearing 52 of the arm 54 of the cross head 4, rotatably but not axially movable, rotation of the lever 63 causes the double wedge 42, 44 to be moved slightly from the right to the left, as illustrated in Figure 5. Such shifting of the double wedge causes the reducing roll 25 to be lifted and the gap between the roll and the elongating surface 91 of the carriage 90 75

to be slightly increased for the next succeeding stretching operation. By means of the abutment screw 14 the extent of rotation of the lever 63 which determines the rate of variation of the gap between the reducing roll and the elongating surface 91 of the carriage can be adjusted and controlled.

In the event that it is desired to produce on the stretching machine herein described articles having uniform wall thicknesses or articles having wall thicknesses which are uniform at least for a portion of the length of the work, it is only necessary to disconnect the operation of the pawl and ratchet wheel gearing by removing the abutment pin 62 during the stretching of the whole piece or the parts having the uniform thickness.

During the return stroke of the machine the cam roller 166 of the lever 162 engages the path 168 of the cam plate 138 to effect closure of the clamping device 140, 158. Shortly thereafter the cam roller 134 of the lever 132 engages the cam path 136 of the cam plate 138 and causes the clamping device 122 to open. During this return stroke the reducing roll 25 rotates in a clockwise direction, whereby the projecting pin 60 moves out of engagement with the cooperating abutment pin 62. The lever 63, due to the action of the tension spring 12, is returned to its initial position which is controlled by the adjustment of the abutment screw 14. The pawl 66 slides idly over the teeth of the ratchet wheel during this portion of the stroke.

In approximately the same position of the stretching machine parts, in which the cam roller 134 comes into engagement with the cam path 136, the abutment 102 engages the guide bar 104, which latter part thereby participates in the movement to the left of the carriage and depresses the member 106 by engagement therewith of the sloping portion formed on the under side of the left extremity of the guide bar 104. During the further course of movement to the left of the carriage the arm of the lever 144 engages the abutment 150. Thereafter, as the pivot point 45 of the lever 144 continues its movement to the left, the upper arm of the lever will impart to the closed clamping device 140, 158 a movement in advance of that of the carriage, the extent of which movement will be limited by the position of the abutment 156. Thus, the article to be stretched is advanced, increment by increment, into new stretching positions and the rate of feed is adjustably controlled by means of the abutment screw 154 and the abutment 152.

During the end of the return stroke the slide-block 92 is restored to its initial position by means of the abutment 102. Thereby the member 108 is permitted to return to its uppermost position due to the action of the compression spring 112, whereupon the slide-block 92 is then held in position by means of the shoulders 116, 118.

At the end of the return stroke the stretching machine parts have been restored to the position illustrated in Figure 1. A new increment or section of the article to be stretched is ready for the stretching operation and the gap between the roll and the elongating surface 91 has been slightly increased. Inasmuch as the roll is lifted not during the stretching operation proper but after finishing the stretching stroke, in the manner described, it is not possible to produce articles of entirely uniform tapering wall thicknesses. The articles produced according to this invention actually consist of small sections or increments of uniform wall thickness, of which sections the one

immediately following shows a slightly greater thickness than the preceding one. As the difference in the wall thicknesses between one section and the following one is less than .0004 inch, such deviations from the actual geometrical shape are of no practical importance with sheets of tapering wall thicknesses.

It must be further realized that the roll acts during each stretching operation also on precedingly stretched sections, thus counteracting the abrupt formation of steps. If necessary, feeding rates can be adjusted so small that there will be practically no deviation from an accurate geometrical shape. In producing articles of sharply tapering wall thicknesses, any deviation from the exact geometrical shape can to a large extent be avoided by giving such portion of the stretching surface of the carriage as is in engagement with the roll toward the end of the working stroke a certain incline with respect to the portion being in engagement with the roll during the first part of the working stroke. Thus, referring to Figure 1, as shown, the elongating surface 91 is parallel with the line of the stroke of the roller 25 with the result that the thickness of the reduced stock for each stroke will be uniform. If, however, the elongating surface 91 is inclined toward the stroke of the roller 25 so that if the stroke of the roller 25 were indefinitely lengthened it would engage the elongating surface 91, the thickness of the worked metal will not be uniform but in itself will be tapering so as to make it possible to taper the metal for each stroke to approximately the taper of the finished sheet. Thus, if the stroke of the roller 25 between the position shown in Figure 1 and the position shown in Figure 3 is considered to be X and if the clearance between the roller 25 and the elongating surface 91 is increased for each stroke by the distance Y, it follows that if the elongating surface 91 be tilted so that the clearance at the beginning of the stroke in Figure 2 between the roller 25 and the elongating surface 91 (see Figure 1) is Z and the clearance between the roller 25 and the elongating surface 91 at the end of the stroke or position shown in Figure 3 is Z-Y, then inasmuch as Y is the increased clearance for each stroke, Z-Y must have been the clearance between the roller 25 and the elongating surface 91 in Figure 2 at the beginning of the previous stroke with the result that each stroke gives a tapering surface to the limited portion shaped corresponding to the general taper of the finished article.

It is important that the disclosure of my Patent No. 1,982,544 be borne in mind, because the method of stretching the metal makes it possible to obtain a low pitch tapered sheet which could not be obtained by other known methods. As is said in that patent, stretching the metal in a direction away from the unlengthened portion and not as in known processes in the opposite direction permits of a rate of elongating of cold metal, not otherwise possible. Because of this, it is possible to utilize an automatic means varying the thickness of the finished product whereby the generally uniform taper will result.

Having thus described the invention, what we claim as new and desire to secure by Letters Patent of the United States, is:

1. A stretching apparatus of the character described for producing solid metal articles of varying thickness, comprising, in combination, a supporting surface for an article to be worked, an elongating surface inclined to the supporting surface, means for reducing and drawing out incre-

ments of the article against said elongating surface in a direction away from the remainder of the article, means for periodically effecting relative movement between said support and said article to expose succeeding portions of the article to said reducing and drawing means for successive lengthening, and means for varying the distance between said reducing and drawing means and the elongating surface directly with the advance of the article through the stretching apparatus.

2. A stretching apparatus of the character described for producing solid metal articles of varying thickness, comprising, in combination, a supporting surface for an article to be worked, an elongating surface inclined to the supporting surface, means for reducing and drawing out increments of the article against said elongating surface in a direction away from the remainder of the article, means for periodically effecting relative movement between said support and said article to expose succeeding portions of the article to said reducing and drawing means for successive lengthening, and means for varying the distance between said reducing and drawing means and the elongating surface directly with the advance of the article through the stretching apparatus during those parts of the strokes wherein reducing and elongating do not take place.

3. An apparatus of the character described in claim 1, wherein the means for varying the distance between the reducing and drawing means on the elongating surface are automatically actuated by means operable during only that part of the stroke wherein no compressive strain is caused by the variation of said distance.

4. A stretching apparatus of the character described comprising, in combination, a supporting

surface for an article to be worked, an elongating surface inclined to the supporting surface, means for reducing and drawing out increments of an article advanced from the supporting surface toward the elongating surface in a direction away from the unworked portion of the article, a reciprocating carriage for the supporting surface and the elongating surface for bringing the reducing and drawing means into operable relationship with the elongating surface, and means for lowering the reciprocating carriage toward the end of the working stroke and lifting it again toward the end of the idle stroke.

5. An apparatus of the character described in claim 4 comprising a wedge shaped slide block guided in the base plate of the apparatus on which slide block the reciprocating carriage is slidably mounted, and abutments formed on the reciprocating carriage adapted to move the slide block in opposite directions so as to lower the slide block and the reciprocating carriage toward the end of the working stroke and to lift them toward the end of the idle stroke.

6. The method of producing a solid metal article having longitudinally a generally tapering cross section which comprises advancing the metal article beyond the edge of a supporting surface, moving a reducing and drawing means into engagement with the metal article along a path oblique to the supporting surface and parallel to an elongating surface in a direction away from the unworked portion of the metal article, and increasing the clearance between the elongating surface and the reducing and drawing means by regular steps as the metal strip is advanced beyond the edge of the supporting surface.

FRITZ SINGER.
ALFRED LIEBERGELD.
